UNITED STATES PATENT OFFICE.

LOUIS J. KIEFFER, OF BOWLING GREEN, KENTUCKY.

DOUBLE-DERAIL APPLIANCE.

1,000,680.

Specification of Letters Patent. Patented Aug. 15, 1911.

Original application filed February 8, 1910, Serial No. 542,779. Divided and this application filed April 10, 1911. Serial No. 620,108.

To all whom it may concern:

Be it known that I, LOUIS J. KIEFFER, a citizen of the United States, residing at Bowling Green, in the county of Warren and State of Kentucky, have invented certain new and useful Improvements in Double-Derail Appliances, of which the following is a specification.

My invention relates to safety devices for railways at their sidings, and more specifically to a particular arrangement of co-operating derailers—one located in the main track and the other in the siding—and to the special construction of these derailers.

This application is practically a division of application Serial Number 542,779.

My object is to provide means for effectively safeguarding trains against a large class of accidents which are liable to occur in connection with or on account of railway sidings on main tracks, such, for instance, as headend collisions and rearend collisions in sidings; rolling stock on either 25 the main track or siding running through a closed switch and splitting the same; a train on the main track running into a train moving into or out of the siding; and a train on the main track sideswiping rolling stock 30 fully in the siding but standing too near the end thereof.

My invention consists in certain novel parts and combinations hereinafter described and claimed, and illustrated in the 35 accompanying drawings.

An important feature of my invention is the combination with a main railway track and its co-operating siding, of a derailler for each track, said derailers being connected 40 with the switch operating mechanism and so related to the switch points and to each other that when either track is opened and the other thereby closed, their respective derailers will also be opened and closed simultaneously therewith, to permit the unobstructed passage of trains on the open track and to forbid the passage of trains into or too near the end of the closed switch on the other track.

50 Another object is to provide a derailler so constructed that if the operating mechanism connected therewith should get broken the derailler will automatically move away from the track and will not shift around onto the track where it would be a menace to any rolling stock that might happen to pass.

Other objects will appear in the subjoined description.

Special attention is called to the fact 60 that my arrangement not only provides a derailler for each track,—whereas heretofore only sidings have been provided with derailers—but that my derailers are so related to each other that neither one of them 65 can be moved without suitably moving the other; and not only this, but that they are likewise so related to the switch points that every time the derailers are moved, the switch points receive an appropriate movement answerable thereto. That is to say, 70 that, whenever either one of the tracks is opened for a train to pass the other is not only closed, but is also guarded by its derailler to prevent any rolling stock from 75 passing out of the closed track to be collided with by the coming train, or from moving near enough to the end of the closed portion of track to be sideswiped by said train. For it must be borne in mind that 80 not only is there the possibility, under ordinary circumstances, of an engineer forgetting his orders and running out of a closed track and splitting the switch points, or of moving up too close to the end of the 85 switch, but rolling stock on a closed track may be blown by a storm, or otherwise moved too near the end of the track where it will be run into or sideswiped by a train 90 passing on the open track.

In the drawings, I have shown a section of a main line of railway and one end of a co-operating siding provided with my improvements. It is, of course, understood that each end of the siding is provided with 95 similar mechanism.

Referring to the drawings:—Figure 1, shows my co-operating derailler on a railway track in the position they occupy when the main track is open, their position when the 100 switch is open being indicated in dotted lines. Fig. 2, is a top plan view on an enlarged scale showing one of my derailers in operative relation to a rail, with the pilot wheel of a locomotive about to run upon it. 105 Fig. 3, is a transverse sectional view of one of the derailers, showing it in operative relation to its support and to the railway track, with a car wheel approaching the derailler to be derailed thereby.

I prefer to make my derailers rights and lefts, since, as a rule, they will be more durable, and certain in operation when constructed in that way; but I do not mean by

this statement to divert attention from the fact that the leading idea of my invention is the coöperation of the derailers together, so that when the need of meeting certain situations, as an entirety, is faced, my derailers are complementary one to the other; and it must be borne in mind that this is a very different thing, from simply having an independent derailler in each track.

10 It should also be noted that in operation not only are my derailers complementary to each other, but their united action is also complementary to that of the switch points.

The letter "A" indicates a main line of 15 railway track, and "B", its coöperating siding.

The numeral "1" indicates the switch stand from which the switch points are operated, and this stand through the mediation 20 of the rod "2", the crank "3", the rod "4", the crank "5", and the rod "6" is operatively connected with the switch derailler "7", which in turn is connected by the rod "8" with the main track derailler "9".

25 The relation of these several parts to each is such that the switch points and derailers are always operated simultaneously; *i. e.*, no one of these can be operated without suitably operating the other.

30 In Fig. 1, I have shown my derailers connected together by a single rod "8", but in practice it will often be found advisable to move the main track derailler "9" farther up the main line from the switch points, in 35 which case there will have to be a plurality of rods, cranks, etc., to form the connection between the two derailers, and sometimes it may be necessary to change the whole arrangement of rods and cranks, but in every

40 case the arrangement must be such that when either of the derailers is in operative position the other will be in inoperative position; and the derailers must be so related to the switch points that when either track

45 is opened and the other thereby closed, the derailler in the open track will be opened and the derailler in the closed track closed. It will also sometimes be found advisable to so arrange the line of connection between 50 the switch stand and the derailers that the main track derailler "9" will be reached first, and the switch derailler operated therefrom.

55 My derailers "7" and "9" are mounted on blocks or supports 7^a and 9^a, respectively, and the tops of these blocks incline downwardly and inwardly from their respective tracks, so that if the operating mechanism of the derailers gets broken they will have 60 imparted to them a certain tendency to move away from their respective tracks into inoperative position. In order, however, that this movement of the derailers may not be so far as to bring their rear ends too near 65 the tracks where they would endanger pass-

ing trains, I provide the inclined blocks 7^a and 8^a with stop pins 10 and 11.

In order to make more certain and positive the movement of the derailers into inoperative position, in case their operating mechanism should get broken, I provide them with the tension springs 12 and 13 suitably attached thereto, and adapted to draw the derailers inwardly away from their respective rails. However, it will be seen 75 that a difficulty here presents itself, for since the derailers are connected together by the rod 8, these springs act one against the other, and if the springs are of equal strength, one will nullify the force of the other, so that they had as well not be there. This difficulty, however, is avoided by making one of the springs stronger than the other, so that the derailler to which it is attached will be the ruling derailler in case 80 the operating mechanism between the switch stand and the derailers gets broken; and since it is usually more important to guard the main track derailler than the other, the stronger spring 13 is usually attached to the 85 main track derailler. If then the connection between the switch stand and the derailers is broken the main track derailler will be certain to be moved into inoperative position. If, in addition to this, the connection 90 between the two derailers is broken, then the side track derailler "7" will also be drawn inwardly by its individual spring. But so long as the rod "8" is intact the spring 12 could be dispensed with, for through this 95 rod the derailler "7" would be operated by the spring 13 of the ruling derailler.

One of my derailers is illustrated on an enlarged scale, in plan view, in Fig. 2 of the drawings, and in section in Fig. 3, and as both derailers are substantially alike except that they are preferably rights and lefts, it is only necessary to describe one of them.

From Fig. 2 it will be seen that the derailler therein illustrated is provided with front and rear ears 14 and 15, which adapt it to be suitably engaged by the operating mechanism that shall be connected therewith from time to time as need may require. Each of these ears is preferably provided with two openings, though as a rule only one will be needed.

The projecting portion "16" of the derailler is adapted to overlie the top of the rail "17" when in operative position; and the rib or shoulder "18" at the front end of the derailler strengthens it at that end where it first receives the impact of the wheels and serves to deflect the wheels from the rail.

The inclined support 9^a is clearly shown in section in Fig. 3. This support is provided with a bore having a conical bottom 19, with an opening 20 leading down from

its apex through the support, for purposes of drainage.

The derailler is provided in its side adjacent to the rail with a groove 21 adapted to receive the inner side of the rail. It also has an integral projection 22 on its under side which fits the bore 19 of the support 9^a, and terminates in a pin 23 carrying a cotter 24 in its lower end to securely hold the derailler in the support 9^a upon which it rotates.

There is sufficient space between the cotter 24 and the under side of the support 9^a to allow the derailler slight upward and downward play on its support to cause it to work perfectly.

As an illustration of the operation of my device let us suppose that a train has entered the siding for a fast train to pass on the main track, let us say, coming from the left, and that the switch points and deraillers are in the position shown in Fig. 1. Now, if, as the fast train just described, is passing (from the left) on the main track, the engineer in the siding should inadvertently attempt to follow too soon and be in danger of running into the point of the switch and getting his engine sideswiped by the passing train, his engine would be ditched by the switch derailler. Again, if the parts are in the position shown in Fig. 1 and empty cars are standing in the siding they cannot be moved by a storm, or other unforeseen cause, near enough to the end of the siding to be struck by a train passing on the main track, for the switch derailler would always be an unerring safeguard against such a contingency.

These deraillers also afford a most convenient and ever ready means of ditching runaway trains.

Having thus described my invention, what I claim as new and desire to secure by Letters Patent is:—

1. In coöperating deraillers, the combination with a main track and a coöperating siding, of a derailler for each track and means for simultaneously operating said deraillers.

2. In coöperating deraillers, the combination with a main track and a coöperating siding, of right and left deraillers for the respective tracks, and means for simultaneously operating said deraillers.

3. In coöperating deraillers, the combination with a main track and a coöperating siding, of a derailler for each track, said deraillers being adapted to move simultaneously one into operative position and the

other into inoperative position and vice versa; and operating mechanism for said pair of coöperating deraillers.

4. In coöperating deraillers, the combination with a main track and a coöperating siding, of a derailler for each track, said deraillers being connected together and arranged to operate in conjunction with the switch points to open and close as their respective tracks open and close.

5. In coöperating deraillers, the combination with a main track and a coöperating siding, of a derailler in each track, said deraillers being connected together and adapted to move simultaneously, one into operative position and the other into inoperative position, and vice versa; and a spring connected to one of said deraillers and arranged to move the same into inoperative position.

6. In coöperating deraillers, the combination with a main track and a coöperating siding, of a derailler in each track, said deraillers being connected together to operate in conjunction with each other; and a spring attached to each of said deraillers to move it into inoperative position, one of said springs being stronger than the other.

7. In coöperating deraillers, the combination with a main track and a coöperating siding, of a derailler for each track, said deraillers being connected together to operate in conjunction with each other; operating mechanism for the pair of deraillers; and means for giving one of said deraillers control of the other in case said operating mechanism is broken or disconnected.

8. A derailler adapted to coöperate with a railway track, and means designed to automatically move the derailler away from said track into inoperative position, when the operating mechanism of the derailler is broken or disconnected.

9. A derailler adapted to coöperate with a railway track, and provided with an inclined bearing, said derailler being rotatably mounted on said inclined bearing.

10. A derailler adapted to coöperate with a railway track, and provided with a spring adapted to move the derailler automatically away from the track into inoperative position.

11. A derailler adapted to coöperate with a railway track and mounted on a support, having a bore with a concave bottom, and an opening leading downwardly from the center of said bore, through said support for drainage purposes; and a projection on the derailler fitting said bearing.

In testimony whereof I affix my signature in presence of two witnesses.

L. J. KIEFFER.
